UNITED STATES PATENT OFFICE.

EDWARD G. ROWLEY, OF BELLEVILLE, NEW JERSEY, ASSIGNOR TO UNDERWOOD
TYPEWRITER COMPANY, OF NEW YORK, N. Y., A CORPORATION OF DELAWARE.

TYPEWRITING MACHINE.

Application filed October 5, 1923. Serial No. 666,682.

The invention relates to ribbon-vibrating mechanism, and is applied to a typewriting machine in which the platen is on a frame shiftable between case-positions, and in which the ribbon-vibrator is carried by the shift-frame and has a variable throw for presenting a selected color-zone of a bi-chrome ribbon to the printing point, and in which the ribbon-vibrator may be silenced 10 when it is desired, as for stenciling.

In machines of this character, since the ribbon-vibrator is generally operable by all of the type-keys, it is convenient to actuate the ribbon-vibrator through, and by means 15 of, the universal bar which controls the step-by-step letter-feed of the platen-carriage upon operation of any type-key. It follows that certain of the mechanism for operating the ribbon-vibrator is on the main 20 frame of the machine, whereas the ribbon-vibrator itself and certain actuating means therefor are on the shift-frame.

An object of the present invention is the provision of novel and simple means where- 25 by to connect the vibrator parts on the main frame with the vibrator parts on the shift-frame, so that there will be no interference with the movement of the shift-frame, and so that the movement of the vibrator, in 30 either case-position of the shift-frame, may be the correct movement truly to present any selected color-zone of the ribbon to the printing-point, without so-called "bleeding" of the ribbon, that is to say, without possibility 35 of the type overlapping the boundary zones of the ribbon in its impact against the platen.

In typewriting machines, the ribbon-vibrator is ordinarily actuated by means of a 40 lever connected thereto; and a feature of the present invention is the provision of novel and simple means for positively controlling the movement of such lever, so that the same cannot be overthrown, and cannot overthrow 45 the vibrator under any conditions. In the preferred form of the invention, the means by which the vibrator-lever is actuated, and is controlled against overthrow, is a toggle connected, on the one hand, to the vibrator-lever, and, on the other hand, to the frame 50 on which the vibrator-lever is fulcrumed; the extreme throw of the vibrator-lever being determined by the straightened position of the toggle.

A feature of the invention is the provision 55 of means whereby the fulcrum of the toggle or its equivalent may be made stationary with respect to the frame on which the same is mounted; thereby obviating the necessity of mechanism for preventing overthrow of 60 the toggle as a whole, and considerably simplifying the action and number of parts required to operate the vibrator.

Other features and advantages will here- 65 inafter appear.

In the accompanying drawings.

Figure 1 is a view, in side elevation, partly cross-sectional, of a typewriting machine embodying the present invention.

Figure 2 is a view, in front elevation, 70 partly cross-sectional, on the line 2-2 of Figure 1; certain of the parts being broken away for clearer illustration; and the ribbon-vibrator and ribbon-vibrator-actuating parts being in normal position, but set for 75 printing in the upper or black zone of the ribbon.

Figure 3 is a view similar to Figure 2, except that the type-key has been actuated 80 to throw the ribbon to position for printing in the upper or black zone of the ribbon.

Figure 4 is a view, in front elevation, showing the ribbon-vibrator in normal position, but the parts set for printing in the lower or red zone of the ribbon. 85

Figure 5 is a top plan view of the mechanism shown in Figures 2, 3 and 4.

The machine herein illustrated is of the front-strike type, and comprises character-keys 10, which throw type-bars 11 upward and rearward against the front of a platen 12, which is journaled in a sheet-metal carriage 13. The carriage travels to the left under the control of escapement mechanism, not shown, and is provided with roller-bearings 14 and 15, by which it travels on sheet-metal tracks 16 and 17. The tracks 16 and 17 form part of a shift-frame, which also includes a downwardly-extending rear member 18 and forwardly-extending side members 19; the latter being provided with pivot-screws 20, by means of which the shift-frame is pivoted at either side to one of a pair of upper long links 21, these links being, in turn, pivoted to the main frame 22 by pivots 23 nearly behind but somewhat below the normal position of the pivots 20. 100

For guiding the shift-frame, there is pro-

vided a pair of links or rock-arms 24, one at each side of the machine, and each provided with a stub shaft 25, on which rests a yoke 26 formed in the corresponding side piece 19 of the shift-frame; the links 24 being fast at their rear ends to a transversely-extending rock-shaft 27, which is encircled by a spring, not shown, so tensioned as to assist in lifting the shift-frame to upper case.

For lifting the shift-frame, there is provided, at one side of the keyboard, a shift-key 29, fulcrumed on a short shaft 30 on a standard 31 rising from a cross-tie 32, which connects the sides of the main frame. The shift-key-lever is provided with a rearward extension 33 underlying the elbowed end 34 of a sheet-metal rock-arm 35 fast on the shaft 27. It follows that, when the shift-key 29 is depressed, its rearward extension 33 lifts the rock-arm 35, thereby rocking the arms 24 upward so that the stub-shafts 25 on the latter will lift the shift-frame. The shift-key 29 may be depressed until the shift-frame is arrested by inwardly-turned heels 36 thereon, one on each side plate 19 thereof, and such heels strike set screws 37 on the turned-over ends 38 of arms or brackets 39 secured to a cross-piece 40 which connects the side plates of the main frame at the lower rear portion of the latter. When the shift-frame is shifted to this position, the types 41 on the type-bars 11 are effective to print, instead of the normally effective lower-case types 42. Set screws 43, one at each side of the machine, in the brackets 39, by engagement with the under faces of the heels or flanges 36, arrest the shift-frame in normal lower-case position when it is allowed by gravity to return to such position upon release of the shift-key.

The character-keys 10, when actuated, move character-key-levers 44 around a common fulcrum-plate 45, supported on the cross-tie 40. Each key-lever 44, when actuated, moves against the tension of a spring 46 to swing a bell-crank, not shown, and, through the latter, to pull on a link, not shown, to cause its type-bar 11 to swing.

To cause the carriage to move from one letter-space position to another, while typing, there is provided a universal bar 47, supported by means of arms 48 on a rock-shaft 49; with which universal bar the key-levers engage, when depressed, by means of shoulders or lugs 50 on the key-levers. The rock-shaft 49 is journaled in brackets 51, one at each end thereof, secured to the cross-bar 40. An arm, not shown, on the universal bar connects with and operates escapement mechanism, not shown, for controlling the letter-feed movements of the carriage; so that, upon each depression of any letter or numeral key-lever, the carriage may have a letter-space advance under the action of the spring-drum. Escapement mechanism

suitable for this purpose is shown in United States Letters Patent to Dobson, No. 1,417,304, dated May 23, 1922.

Except when the ribbon is to remain in neutral position, as, for instance, in stenciling, the ribbon is to be vibrated upon each operation of a character-key, whether the platen is in lower or upper case-shift position; and, in accordance with the present invention, a bichrome ribbon may be employed, in which event the ribbon may have a variable vibration to present one or the other of the color-zones thereof to the printing point. The ribbon 52, comprising color-zones 53 and 54, and wound upon spools, 80 not shown, is threaded through the eyes 55 of a ribbon-carrying vibrator, which comprises arms 56, connected at their lower ends to form a U-shaped structure 57. The ribbon-vibrator has up-and-down movement on 85 a guide 58, secured by screws 59 to a rail 60, which is unitary with the front carriage-guide-rail 16 of the shift-frame, and which depends vertically from the forward edge of the latter, and extends lengthwise of the 90 shift-frame, being secured at each end to brackets (not shown) on the side plates 19 of the shift-frame. The ribbon-vibrator guide comprises a pair of upright arms 63, which are embraced by ears 64 turned 95 around the same, one from each of the arms 56 of the ribbon-vibrator. The base-piece of the ribbon-vibrator guide is slotted at 65 to provide a guide-way for a stud 66, by means of which the ribbon-vibrator is connected to one end of a lever 67. The lever 67 extends right-ward, lengthwise of the platen, and at its right-hand end has an arcuate slot 68 therein to receive a pin 69 on a shift lever 70 pivoted at 100 71 to a plate or bracket 72, secured by screws 73 to the shift-frame front rail 60, and by screws 74 to the right-hand side plate of the shift-frame. The lever 67 is therefore, in effect, fulcrumed on the plate or bracket 72. 110 The effective arm of the lever is, however, an arm of variable length, in order that, when the lever is actuated, by means presently to be described, it may effect a variable throw of the ribbon-vibrator to present 115 either of the black or red zones of the ribbon to the printing-point.

In Figure 3, the shift lever 70, carrying the fulcrum-pin 69 of the lever, is shown in its extreme right-hand position with the pin 120 69 at the outer end of the slot 68. In this position of the lever 70, the lever 67, when swung up, will have such movement as is sufficient to present the upper or black color zone 53 of the ribbon to the printing-point. 125 In Figure 4, the lever 70 is shown in its extreme left-hand position with the fulcrum-pin 69 of the lever 67 at the left-hand end of the slot 68. In this latter position of the lever 70, the lever 67, when swung on 130

its fulcrum, will effect a greater movement of the ribbon-vibrator, sufficient to present the lower or red color zone 54 of the ribbon to the printing-point. At an intermediate or central point of the slot 68, a recess 75 is offset therefrom; and, when the lever 70 is swung to such position that the fulcrum-pin 69 registers with this recess 75, upward movement of the lever 67 will similarly cause the fulcrum-pin 69 to enter the recess 75 without movement of the ribbon-vibrator. In this latter position, the ribbon-vibrator is then silenced, as for stenciling. The lever 70 carries a finger-piece 76, by means of which it may be thrown to any one of the three positions mentioned, and a spring-detent 77 on the arm, by registration with pockets 78 in the plate or bracket 72, serves to hold the lever 70 in selected position. Stop-pins 79 and 80 may serve to determine the extreme right and left hand positions, respectively, of the lever 70. The plate 72 may be suitably marked as at 81, 82, 83, to indicate the proper positions of the lever 70 for writing in black, red or for neutral, respectively.

The lever 67 is actuated on each actuation of a type-key by the following means. On an arm 84, forming part of the bracket 72, is pivoted at 85 one end of a toggle 86-87. The other end of the toggle is pivotally connected at 88 to the lever 67, between the fulcrum of the latter and the connection of the same to the ribbon-vibrator. A spring 89, connected at one end to the bracket-arm 84 and at its other end to the toggle, normally holds the toggle in the Figures 2 and 4 position, and returns the toggle to such position when free to do so; acting through the toggle also to return the lever 67 and ribbon-vibrator to normal position. Connected to the toggle-arm 86 is a link 90 in the form of a stiff wire, one end of which is hooked into a hole 91 in the toggle-arm 86 in such manner as to allow swing of the link 90 with respect to the toggle-arm 86. The link 90 extends leftward, lengthwise of the platen, from the toggle-arm 86, and at its left-hand end is offset at 92 (see Figures 2 and 5), to be hooked into a hole 94 in an arm 95; forming part of a bell-crank lever pivoted at 96 to a bracket 97 rising from the cross-piece 40 of the main frame. The opening 94, into which the link 90 is hooked, is of sufficient size to permit of up-and-down swing of the link as the right-hand end thereof moves with the shift-frame. The bell-crank, of which the arm 95 forms part, comprises another arm 98, which projects rightward in front of, and across the path of movement of, an arm 99, which is fast to, and extends vertically upward from, the rock-shaft 49, to which, as aforesaid, the universal bar 47 connects.

It follows that, whenever a type-key is

depressed to actuate the universal bar and rock the shaft 49, the arm 99 rocks the bell-crank 95-98 clockwise (Figure 5), causing the link 90 to be drawn leftward. This movement of the link 90 straightens the toggle from either its Figure 2 or Figure 4 position to its Figure 3 position, thereby throwing up the lever 67 with the ribbon-vibrator (except when the fulcrum-pin 69 of the lever registers with the recess 75, as for stenciling). The spring 89, which returns the toggle-joint to normal position, draws the link 90 rightward when the key is released, and thereby returns the bell-crank 95-98 to normal position. It will be noted that, when the toggle is straightened out, as in Figure 3, further upward movement of the lever 67 and ribbon-vibrator is impossible. Overthrow of the ribbon is thereby absolutely prevented.

It will also be noted that the ribbon-vibrator has a straight-line up and down movement made possible by the disposition of the two ears 64 and the stud 66 as shown and described; that the end of the lever 67 pivoted to a part of the stud 66 prevents longitudinal movement of the lever and that the opposite end of the lever floats upon the fulcrum pin 69; that the stud 66 strikes the bottom of the slot 65 for a normal inoperative stop and that the straightened-out toggle automatically stops the upward throw of the vibrator at either ribbon-throw position; that the stopping of the upward throw of the ribbon by the straightened-out toggle provides a retarded transmission to the vibrator, that becomes nil at the end of each key-stroke and wholly removes the annoying "kick" at the keys, as when fixed stops are employed that suddenly arrest a vibrating part of the ribbon-shift control; and that the whole ribbon-vibrating and ribbon-shifting mechanisms are co-operatively mounted upon the shifting platen-frame.

Variations may be resorted to within the scope of the invention, and portions of the improvements may be used without others.

Having thus described my invention, I claim:

1. In a typewriting machine, a platen, a ribbon-vibrator, a lever for operating the ribbon-vibrator, means for shifting the fulcrum of the lever, to vary the throw of the vibrator, to present to the printing-point a selected color-zone of a bichrome ribbon, a jointed lever pivotally connected to the ribbon-vibrator lever between the fulcrum thereof and the ribbon-vibrator, for throwing the ribbon-vibrator lever a distance predetermined by the straightened-out length of said jointed lever, type-keys, and means for actuating the jointed lever from the type-keys.

2. In a typewriting machine, a platen, a ribbon-vibrator, a lever for operating the

ribbon-vibrator, means for shifting the fulcrum of the lever, to vary the throw of the vibrator, to present to the printing-point a selected color-zone of a bichrome ribbon, a 5 toggle connected to the vibrator-lever between the fulcrum of the latter and the ribbon-vibrator, type-keys, and means for actuating the toggle from the type-keys.

3. In a typewriting machine, a platen, a 10 ribbon-vibrator, a lever for operating the ribbon-vibrator, means for shifting the fulcrum of the lever, to vary the throw of the vibrator, to present to the printing-point a selected color-zone of a bichrome ribbon, a 15 toggle connected to the vibrator-lever between the fulcrum of the latter and the ribbon-vibrator, type-keys, a universal bar adapted to be actuated by the type-keys, and means for actuating the toggle from the universal 20 bar.

4. In a typewriting machine, a platen, a ribbon-vibrator, a lever for operating the ribbon vibrator, means for shifting the fulcrum of the lever, to vary the throw of the 25 vibrator, to present to the printing-point a selected color-zone of a bichrome ribbon, a toggle connected to the vibrator-lever between the fulcrum of the latter and the ribbon-vibrator, type-keys, a universal bar 30 adapted to be actuated by the type-keys, a link connected to the toggle, and means for actuating the link from the universal bar.

5. In a typewriting machine, a platen, a ribbon-vibrator, a lever for operating the 35 ribbon-vibrator, means for shifting the fulcrum of the lever, to vary the throw of the vibrator, to present to the printing-point a selected color-zone of a bichrome ribbon, a toggle connected to the vibrator-lever between the fulcrum of the latter and the ribbon-vibrator, type-keys, a universal bar 40 adapted to be actuated by the type-keys, a link connected at one end to the toggle, a rocker to which the link is connected at its 45 other end, and an arm connected to the universal bar for actuating the rocker.

6. In a typewriting machine, a platen, a ribbon-vibrator, a lever for operating the ribbon-vibrator, means for shifting the fulcrum of the lever, to vary the throw of the 50 vibrator, to present to the printing-point a selected color-zone of a bichrome ribbon, a toggle connected to the vibrator-lever between the fulcrum of the latter and the ribbon-vibrator, type-keys, a universal bar 55 adapted to be actuated by the type-keys, a link connected at one end to the toggle, a bell-crank to which the link is connected at its other end, a rock-shaft upon which the 60 universal bar is mounted, and an arm on the rock-shaft for engagement with the bell-crank to actuate the same when the universal bar is actuated.

7. In a typewriting machine, a platen, a 65 frame for the platen, means for shifting the

frame between case-positions, a ribbon-vibrator on the case-shift frame, a lever connected to the ribbon-vibrator at one end, and at its other free end having a slot, a lever pivoted on the shifting frame and having a pin to engage within the slot and support the free end of the first-named lever, means for shifting the pin along the slot to vary the throw of the vibrator-actuating lever to present to the printing-point a selected color-zone of a bichrome ribbon, type-keys, and means for actuating the vibrator-lever from the type-keys. 75

8. In a typewriting machine, a platen, a frame for the platen, means for shifting the frame between case-positions, a ribbon-vibrator on the case-shift frame, a lever connected to the ribbon-vibrator at one end, and at its other free end having a slot, a lever pivoted on the frame on which a pin is mounted, to engage the slot and support the free end of the first-named lever, manual means for shifting the pin-carrying lever to change the position of the pin in the slot, and thereby to vary the throw of the vibrator-actuating lever to present to the printing-point a selected color-zone of a bichrome ribbon, type-keys, and means for actuating the vibrator-lever from the type-keys. 85

9. In a typewriting machine, a platen, a frame for the platen, means for shifting the frame between case-positions, a ribbon-vibrator on the case-shift frame, a lever fulcrumed on the case-shift frame for actuating the ribbon-vibrator, manually-operable means on the shift frame for shifting the fulcrum of said lever to vary the throw of the ribbon-vibrator to present to the printing-point a selected color-zone of a bichrome ribbon, a two-part jointed lever having one part 100 pivoted on the case-shift frame and the other part connected to the vibrator-lever between the fulcrum of the latter and the vibrator, type-keys, and means for actuating the jointed lever from the type-keys. 105

10. In a typewriting machine, a platen, a frame for the platen, means for shifting the frame between case-positions, a ribbon-vibrator on the case-shift frame, a lever fulcrumed on the case-shift frame for actuating the ribbon-vibrator, means for shifting the fulcrum of such lever to vary the throw of the ribbon-vibrator to present to the printing-point a selected color-zone of a bichrome ribbon, a toggle on the case-shift frame connected 115 to the vibrator-lever, type-keys, and means for actuating the toggle from the type-keys. 120

11. In a typewriting machine, a platen, a frame for the platen, means for shifting the frame between case-positions, a ribbon-vibrator on the case-shift frame, a lever fulcrumed on the case-shift frame for actuating the ribbon-vibrator, means for shifting the fulcrum of such lever to vary the throw of the ribbon-vibrator to present to the printing-point 125 130

- 5 a selected color-zone of a bichrome ribbon, a
toggle on the case-shift frame connected to
the vibrator-lever between the fulcrum of
the latter and the vibrator, type-keys, and
means for actuating the toggle from the
type-keys.

10 12. In a typewriting machine, a platen, a
frame for the platen, means for shifting the
frame between case-positions, a ribbon-
vibrator on the case-shift frame, a lever ful-
crumed on the case-shift frame for actuating
the ribbon-vibrator, a toggle on the case-
shift frame connected to the ribbon-vibrator
lever, type-keys, a universal bar actuatable
15 from the type-keys, a rock-shaft on which
the universal bar is mounted, a link connect-
ed to the toggle at one end, and an arm on
the rock-shaft for moving the link.

20 13. In a typewriting machine, a platen, a
frame for the platen, means for shifting the
frame between case-positions, a ribbon-
vibrator on the case-shift frame, a lever ful-
crumed on the case-shift frame for actuating
the ribbon-vibrator, a toggle on the case-
shift frame connected to the ribbon-vibrator
lever, type-keys, a universal bar actuatable
25 from the type-keys, a rock-shaft on which
the universal bar is mounted, a link connect-
ed to the toggle at one end, a bell-crank lever
on the main frame, to which the link is con-
nected at its other end, and an arm on the
30 rock-shaft for engagement with the bell-
crank lever to rock the same and actuate the
vibrator when the universal bar is operated.

35 14. In a typewriting machine including a
platen, a platen-carriage, and a frame for
shifting the carriage to upper and lower
case-positions, a ribbon-carrying vibrator
having a straight-line movement, a vibrating
40 lever, and a manually-operable lever for
shifting the fulcrum of said vibrating lever,
the latter having one end pivoted to the vi-
brator to prevent longitudinal movement of
the lever and the other end free to co-
45 operate with said fulcrum-shifting lever, all
mounted upon the shift frame.

50 15. In a typewriting machine including a
platen, a platen-carriage, and a frame for
shifting the carriage to upper and lower
case-positions, bichrome ribbon-vibrating
and ribbon-field-shifting mechanisms wholly
55 mounted upon the shift frame, including a
ribbon-carrying vibrator, a vibratory lever,
a manually-operable lever for shifting the
fulcrum of said vibratory lever, the latter
being connected to said vibrator to prevent
endwise movement of the lever, said vibra-
tory lever formed with means at the free end
to co-operate with said manually-operable
fulcrum-shifting lever, and a toggle to vi-
brate the first-mentioned lever.

60 16. In a typewriting machine including a
platen, a platen-carriage, and a frame for
shifting the carriage to upper and lower
case-positions, a ribbon-carrying vibrator, a
manually-operable ribbon-field-changing le-
65 ver pivoted on the frame and carrying a ful-
crum pin, a lever extending lengthwise of
the platen in front of the carriage and posi-
tively connected at one end to the ribbon-
vibrator and at the other end loosely con-
70 nected to the fulcrum pin, and key-actuated
means on the frame to vibrate the last-men-
tioned lever to present a predetermined field
of the ribbon to the printing point and pre-
75 vent any overthrow of the parts.

76 17. In a typewriting machine including a
platen, a platen-carriage, and a frame for
shifting the carriage, a ribbon-guiding
80 bracket secured to the frame comprising par-
allel guide-arms and a guiding slot parallel
therewith, a U-shaped ribbon-carrying vi-
brator having means to engage with each
guide-arm, a stud at the lower end of the
85 vibrator to engage within the slot on one
side and form a pivot on the other side of
the vibrator, a vibrating lever secured at one
end to said pivot and at the other end formed
with a fulcrum slot, a shiftable fulcrum in
90 said fulcrum slot, and means to vibrate the
lever.

91 18. In a typewriting machine including a
platen, a platen-carriage, and a frame for
shifting the carriage, a ribbon-guiding
95 bracket secured to the frame comprising par-
allel guide-arms and a guide-slot below and
parallel to the arms, a U-shaped ribbon-
carrying vibrator having oppositely-disposed
100 ears to engage with the guide-arms, a stud
secured at the lower end of the vibrator to
slidably engage within the slot and engage
with the end of the slot to arrest the return
movement of the vibrator for a normal in-
operative position, a lever connected at one
105 end to the vibrator and at the opposite end
formed with a slot, a fulcrum pin on the
frame to engage within the last-mentioned
slot, and key-actuated means pivoted on the
frame to vibrate the lever and check the up-
ward movement of the vibrator to prevent
110 overthrow of the ribbon field.

EDWARD G. ROWLEY. [L. S.]
